UNITED STATES PATENT OFFICE

158,068

CONDIMENT SHAKER

James E. Kelly, Los Angeles County, Calif.

Application June 21, 1948, Serial No. 147,099

Term of patent 7 years

(Cl. D44—22)

To all whom it may concern:

Be it known that I, James E. Kelly, a citizen of the United States and resident of Los Angeles County, California, have invented a new, original, and ornamental Design for a Condiment Shaker, of which the following is a specification, reference being had to the accompanying drawing, forming part thereof,

I claim:

The ornamental design for a condiment shaker, substantially as shown.

JAMES E. KELLY.
